UNITED STATES PATENT OFFICE.

CHARLES L. WIGGIN, OF NEENAH, WISCONSIN, ASSIGNOR TO TOY COMPANY OF AMERICA, OF APPLETON, WISCONSIN, A CORPORATION OF WISCONSIN.

WHEELED TOY.

1,413,510.

Specification of Letters Patent. Patented Apr. 18, 1922.

Application filed May 17, 1920. Serial No. 381,843.

To all whom it may concern:

Be it known that I, CHARLES L. WIGGIN, a citizen of the United States, residing at Neenah, in the county of Winnebago and State of Wisconsin, have invented certain new and useful Improvements in Wheeled Toys, of which the following is a specification.

This invention relates to a wheeled toy for small children and is particularly concerned with certain features of construction by which it is adapted to be used either as a vehicle or as a rocker. In this connection I have also combined with other features (1) an eating tray; (2) a detachable connection between certain of the parts such that they may be disassembled to nest within in other parts whenever desired for shipping purposes or otherwise; (3) a walker which may also be used as a rocker or vehicle; and (4) certain features that are characteristic of an aeroplane so as to better amuse the user.

With these as well as other objects in view I will now proceed to a detailed description of the invention, one embodiment whereof is illustrated in the accompanying drawings in the manner following—

Figure 1 is a perspective view of the structure;

Fig. 2 is a central longitudinal section therethrough;

Fig. 3 is a transverse section therethrough taken on line 3—3 of Fig. 4;

Fig. 4 is a plan view;

Fig. 5 is a fragmentary detail in side elevation illustrating the manner in which the wheels are mounted on the rockers; and

Fig. 6 is a sectional detail taken on line 6—6 of Fig. 5.

Referring particular to Fig. 1, the present structure comprises a pair of sides 10 in spaced relation, each of their lower edges 11 being curved to provide a rocker. A front wall 12 and a rear deck 13 extend between the sides 10, as shown. At the forward end of the deck is a substantially vertical wall 14 arranged to provide a back for a seat 15 whose configuration is best shown in Fig. 4, being formed preferably with a forwardly extending rail 16 which may reach to the front wall 12. This seat may also be reinforced on its under side by means of a brace 17 (see Figs. 2 and 3). According to the construction shown, two leg holes 18 are provided one on each side of

the rail 16, through which may be extended the legs of the user for propelling the vehicle over the floor.

At the forward end of the structure is a tray 20 whose ends may extend beyond the sides 10. This tray may be formed to resemble the upper wing of an aeroplane. In furtherance of this effect, a propeller 21 may, if desired, be affixed to the front wall, as shown. The tray may be detachably mounted in place as by means of a pair of rails 22 which are affixed to its under side in such a manner as to abut the inner sides of the two walls 10, bolts 23 being extended laterally through these walls and rails to fasten the tray in place. By some such means of attachment as this, the tray may be readily secured to the structure, or be removed therefrom whenever it is desired, as, for instance, when the entire structure is to be packed for shipment. Depending from the tray I have shown a pair of struts 24 which connect with shelves 25 having a resemblance to the lower wings of an aeroplane, these shelves being supported at their inner ends upon rails 26 which are carried by the sides 10, all as best shown in Fig. 3.

A structure answering to the above description may function as a rocker. Means may be provided additionally for permitting the structure to be wheeled over the floor, and as suggestive of a desirable construction I have arranged within each side wall near its rocker edge a pair of C-slots 30, each having an upper end 31 which is downwardly extended, and a lower end 32 which is upwardly extended; each of these slots provides a guideway within which may be received a sleeve 33 (see Fig. 6) surrounding a pin or bolt 34, the sleeve having a length substantially equal to the thickness of the wall 10; at each end of the sleeve is arranged a washer 35, as shown, to the outer sides of which are a pair of wheels 36 each having a bearing 37 preferably in the form of a sleeve that may be secured in place as by a drive fit; to the outside of each bearing sleeve 37 is another washer 38, one of which may abut a head 39 formed on the pin or bolt 34, the other being held in place by a similar head, a nut, or other fastening device. By this construction is provided two wheels connected together in unitary relation through the medium of a pin or bolt which is provided centrally with a sleeve adapted to

be moved within the C-slot 30 either from a position at its upper end 31 to a second position at its lower end 32, or vice-versa. In Fig. 5 the rollers are shown in full lines as disposed within the lower ends of these slots by which arrangement the entire structure is elevated sufficiently to clear the rockers from the floor so as to permit the structure to be used as a wheeled toy. With the C-slots pointed, as shown, the normal direction of movement is preferably that which is indicated by the arrow in this figure. When the structure is to be used as a rocker, the several wheeled units are moved to the positions indicated by the dotted lines in Fig. 5, so that the rockers are allowed to rest directly upon the floor.

It is to be observed that by this invention I have provided a very simple and inexpensive toy. The parts are so related to each other as to permit the structure to function properly in any of the different capacities suggested. At the tail end a vertical rudder 40 may be carried upon a horizontal rudder 25 41, this latter part being preferably detachable as through the medium of screws 42, so as to nest within the structure when it is to be packed for shipment.

Various changes or modifications which 30 embody the novel features of this invention may obviously be made, but in so far as the same are defined within the claims below, such alternative constructions are to be deemed as within the scope of this patent.

35 I claim:

1. A combined rocker and vehicle comprising, in combination, a pair of spaced rockers each having therein a C-slot with upper and lower extremities, a pair of wheels arranged 40 on opposite sides of each rocker with their centers coincident with the slot, and a common axle pin for each pair of wheels extended through the slot and movable therein intermediate its ends, the slot being formed 45 to normally retain the axle pin in either end position whereby either the wheels or rockers may be presented operatively to the floor, substantially as described.

2. A combined rocker and vehicle comprising, in combination, a rocker in which is formed a slot extending through from side to side and having upper and lower extremities, each of which is formed to provide a seat, an axle pin extended through said slot, 50 a sleeve surrounding the axle pin having its ends coincident with the sides of the rocker and adapted to be shifted into either seat within the slot, a pair of washers carried by

the pin, one at each end of the sleeve, a pair of wheels mounted on the axle, one adjacent each washer and in spaced relation to the sides of the rocker, and means for retaining the wheels in place upon the axle, substantially as described. 60

3. In a vehicle of the kind described, the combination of a pair of sides having their lower edges formed to present rockers between which are a transversely extended front wall and a vertical wall rearwardly thereof, a seat extended between the side 70 walls adjacent the vertical wall, the seat having a narrow forwardly extending portion in the form of a rail which is connected with the front wall whereby openings are provided on either side of the rail forwardly of 75 the seat, wheels adjustably mounted on the rockers having means for maintaining them in a fixed position either below or above the plane of the rockers whereby the device may roll or rock as desired, substantially as 80 described. 85

4. In a vehicle of the kind described, the combination of a rocker in which is formed a slot that extends through from side to side, an axle inserted through the slot and having its ends protruding laterally of the rocker, a pair of wheels mounted on the axle, one on either side of the rocker, and means for spacing each wheel from the rocker, said means including a sleeve which surrounds the axle, and which is disposed entirely within the slot of the rocker, the slot being formed with a plurality of seats 90 within any one of which the sleeve is adapted to rest whereby the wheels may be adjusted either above or below the plane of the rocker, substantially as described. 95

5. A wheeled toy having, in combination, a vertical support, wheels therefor one on either side of the support which is formed 100 with an opening therethrough, a sleeve arranged within the opening and having its ends coincident with the sides of the support, a washer arranged adjacent each end of the sleeve, an axle pin extended through both washers and the sleeve, a bearing sleeve for each wheel arranged axially thereof, each bearing sleeve being received upon the pin one adjacent each of the washers, and means at each end of the pin for holding the adjacent wheel in operative position thereon, 105 substantially as described. 110

CHARLES L. WIGGIN.
